US0D1015373S

(12) United States Design Patent (10) Patent No.: US D1,015,373 S
 (45) Date of Patent:  Feb. 20, 2024

(54) DISPLAY SCREEN WITH ICON

(71) Applicant: NOVADELTA—COMÉRCIO E INDÚSTRIA DE CAFÉS LDA,
 Lisbon (PT)

(72) Inventors: Rui Miquel Nabeiro, Camp Maior (PT); Filipe Alexandre Correia, Mafra (PT)

(73) Assignee: NOVADELTA—COMÉRCIO E INDÚSTRIA DE CAFÉS, LDA,
 Lisbon (PT)

() Term: 15 Years

(21) Appl. No.: 35/512,448

(22) Filed: May 20, 2021

(80) Hague Agreement Data

Int. Filing Date: May 20, 2021

Int. Reg. No.: DM/215914

Int. Reg. Date: May 20, 2021

Int. Reg. Pub. Date: Aug. 27, 2021

(57) CLAIM

The ornamental design for an icon for screen displays, as shown and described.

DESCRIPTION

FIG. 1 is a front view of a display screen with icon, showing a first embodiment of the new design;

FIG. 2 is a second embodiment thereof; and,

FIG. 3 is a third embodiment thereof.

The outermost broken line rectangle shows the display screen, and forms no part of the claimed design. All other broken lines show portions that form no part of the claimed design.

1 Claim, 3 Drawing Sheets

Espresso

Long Drinks
